UNITED STATES PATENT OFFICE.

FRANCIS J. COLE, OF SCHENECTADY, NEW YORK.

LOCOMOTIVE-ENGINE.

1,120,372.

Specification of Letters Patent.

Patented Dec. 8, 1914.

Application filed September 16, 1914. Serial No. 861,981.

To all whom it may concern:

Be it known that I, FRANCIS J. COLE, of Schenectady, in the county of Schenectady and State of New York, have invented a certain new and useful Improvement in Locomotive-Engines, of which improvement the following is a specification.

My present invention is an improvement upon those for which Letters Patent of the United States Nos. 1,024,620 and 1,060,230 were granted and issued to me under dates of April 30, 1912, and April 29, 1913, respectively, and its object is to provide a construction of the type exemplified in said Letters Patent, which shall be desirably applicable in locomotives having fireboxes located above their main driving boxes, and in which, consequently, the use of driving springs which are placed above the frames, as in ordinary practice and in the Letters Patent aforesaid, is rendered impracticable.

The improvement claimed is hereinafter fully set forth.

In the accompanying drawings: Figure 1 is a plan view of a portion of one of the side frame members of a locomotive and of the adjoining parts of a construction embodying my invention; Fig. 2, an outside view, in elevation, of the same; Fig. 3, a view, in elevation, as seen from the front; Fig. 4, a similar view, as seen from the rear; Figs. 5 and 6, views, taken correspondingly to Figs. 1 and 2, respectively, illustrating a modification of structural detail; Fig. 7, a view in elevation, as seen from the rear, of the construction of Figs. 5 and 6; Fig. 8, a similar view, as seen from the front; Figs. 9 and 10, views, taken correspondingly to Figs. 1 and 2, respectively, illustrating another modification of structural detail; Fig. 11, an outside view, in elevation, illustrating another structural modification; and, Fig. 12, a view, in elevation, of the construction of Fig. 11, as seen from the rear.

Referring first to Figs. 1 to 4 inclusive, my invention is, as in Letters Patent Nos. 1,024,620 and 1,060,230 aforesaid, exemplified herein as applied in a locomotive engine, the side frame members of which are of standard bar type, and comprise, so far as relates to the portions thereof in which the driving axles are fitted, top rails, 1, bot-

tom rails, 2, and pairs of connecting pedestal jaws, 3, the lower ends of which are connected by pedestal ties, 5. Each of the driving boxes, 4, is provided with a lower lubricant cellar, 4^a, and is fitted in the pedestal jaws, between a wedge, 4^a, and a shoe, 4^b, and bears on one of the journals, 6^a, of the driving axle, 6, on which the driving wheels, 6^b, are secured. The driving boxes and driving axle journals are, as in the Letters Patent aforesaid, made of materially increased length, as compared with those of ordinary practice prior to said Letters Patent, by the provision of supplemental or auxiliary pedestal jaws, 8, which are secured to the inner sides of the main pedestal jaws, 3, by bolts, 8^a, and are connected by integral transverse webs or braces, 8^b.

The constructions disclosed in my prior Letters Patent before referred to, are well adapted for use in connection with springs which are located above the frames, as is most generally the case. Other designs of spring arrangements, in which the springs are placed below the upper frame rails, are, however, practicable, and in some cases, desirably applicable or positively essential. In order to afford facilities for effecting such application with structural and operative advantage, in the practice of my present invention, a longitudinal equalizer, 9^a, is located adjacent to the inner side of the top rail, 1, of each of the side frame members, above each of the driving boxes, 4, of the main driving axle, 6, on the top of which driving box, and in or near the middle transverse plane thereof, it is directly seated. The end portions of the equalizer, 9^a, are bent or curved downwardly, and the ends of the equalizers are articulated, by pins, 9^c, to spring pockets, 9^b, which are formed integral with the outer end portions of transverse equalizers, 11, which extend across the locomotive, in front and in rear, respectively, of the pedestals, 3. The spring pockets are located, in substantially vertical positions, below the top frame rails, 1, their vertical longitudinal central planes coinciding, as nearly as may be, with those of said frame rails. Supporting springs, 9, 9^a, are seated in the spring pockets, 9^b, and interposed between said pockets and suitable

bearings on the frame rails, for the purpose of transmitting the weight borne by the adjoining portions of the frame members, to the equalizers, 9^b, and thence to the driving boxes, 4, and axle, 6. In the instance shown in Figs. 1 to 4 inclusive, the springs, 9, at the rear ends of the equalizers, are of the plate type, and those, 9^a, at the front ends, are helical. Either or both forms may be applied, in the discretion of the constructor.

Figs. 5 to 8 inclusive illustrate a structural modification embodying the same operative principle, the structural difference consisting in the application of two longitudinal equalizers to each driving box, instead of one as in the instance first described. The two equalizers, 9^{dd}, which correspond in function with the equalizer, 9^a, before described, are, in this case, located in vertical planes adjacent to the ends of the long driving box, 4, and are coupled, by pins, 9^{ee}, extending parallel with the driving axle, 6, to sleeves, 11^a, which are, in turn, pivotally connected to the transverse equalizers, 11, in substantially the middle transverse plane of the driving box, by pins, 9^{ee}. The driving boxes are consequently loaded uniformly throughout their length by the application of the sustained weight to their opposite ends.

The modification shown in Figs. 9 and 10 differs from the construction shown in Figs. 1 to 4 inclusive, only in the particular that the forward spring pockets, 9^a, instead of supporting springs, 9^a, as in the previous instances, are coupled to longitudinal equalizers, 9^{ee}, through which weight is transmitted to the equalizers, 9^a, from points of application located in advance of their forward ends.

As shown in Figs. 11 and 12, the longitudinal equalizers, 9^{ee}, are underhung, that is located below, instead of above, the driving boxes, and are coupled at their ends to the springs, and apply weight to the driving boxes through vertical standards, 9^h, to which they are coupled by pins, 9ⁱ.

It will be seen that under a construction substantially as above described, the weight borne by the supporting springs is applied to the driving boxes at substantially equal distances from their opposite ends, and the application of springs below the upper frame rails is rendered practicable, through connections which are structurally simple and inexpensive, and are readily adaptable to existing conditions of standard locomotive practice.

I claim as my invention and desire to secure by Letters Patent:

1. The combination, with a locomotive frame of bar type, of opposite pairs of inwardly extended pedestal jaws, driving boxes fitting in said pedestal jaws, support-

ing springs located below the upper frame rails, and means for applying weight borne by said springs to the driving boxes, substantially uniformly throughout the length thereof.

2. The combination, with a locomotive frame of bar type, of opposite pairs of inwardly extended pedestal jaws, driving boxes fitting in said pedestal jaws, supporting springs located below and in substantially the middle longitudinal planes of the upper frame rails, equalizers seated on the driving boxes, and connections through which the weight borne by the supporting springs is applied to the ends of the equalizers.

3. The combination, with a locomotive frame of bar type, of opposite pairs of inwardly extended pedestal jaws, driving boxes fitting in said pedestal jaws, supporting springs located below and in substantially the middle longitudinal planes of the upper frame rails, equalizers seated on the driving boxes, and spring pockets articulated to the equalizers and forming the seats of the supporting springs.

4. The combination, with a locomotive frame of bar type, of opposite pairs of inwardly extended pedestal jaws, driving boxes fitting in said pedestal jaws, supporting springs located below and in substantially the middle longitudinal planes of the upper frame rails, equalizers seated on the driving boxes, spring pockets articulated to the equalizers and forming the seats of the supporting springs, and means for connecting the spring pockets of the opposite frame members.

5. The combination, with a locomotive frame of bar type, of opposite pairs of inwardly extended pedestal jaws, driving boxes fitting in said pedestal jaws, supporting springs located below and in substantially the middle longitudinal planes of the upper frame rails, longitudinal equalizers seated on the driving boxes, transverse equalizers articulated at their ends to the ends of the longitudinal equalizers, and spring pockets carried by said transverse equalizers and forming the seats of the supporting springs.

6. The combination, with a locomotive frame of bar type, of opposite pairs of inwardly extended pedestal jaws, driving boxes fitting in said pedestal jaws, supporting springs located below the upper frame rails, equalizers seated adjacent to the opposite ends of the driving boxes and acting to load them uniformly throughout their length, and connections through which the weight borne by the supporting springs is applied to the ends of the equalizers.

7. The combination, with a locomotive frame of bar type, of opposite pairs of in-

wardly extended pedestal jaws, driving boxes fitting in said pedestal jaws, supporting springs located below the upper frame rails, equalizers seated on the driving boxes; 5 equalizers extending longitudinally in the planes of the frame members, and connections from said equalizers to the driving box

equalizers for transmission of weight from the former to the latter and to the driving boxes.

FRANCIS J. COLE.
